YORK, N. Y., A CORPORATION OF NEW YORK.

TELEPHONE-EXCHANGE SYSTEM.

1,403,845.

Specification of Letters Patent. Patented Jan. 17, 1922.

Application filed July 19, 1919. Serial No. 311,959.

To all whom it may concern:

Be it known that we, HENRY P. CLAUSEN and CHARLES L. GOODRUM, citizens of the United States, residing at Mount Vernon, 5 in the county of Westchester, State of New York, and at New York, in the county of New York and State of New York, respectively, have invented certain new and useful Improvements in Telephone-Exchange 10 Systems, of which the following is a full, clear, concise, and exact description.

This invention relates to improvements in telephone exchange systems and has particular reference to a circuit arrangement 15 for switches.

In a trunk-hunting switch, it is desirable that the brushes, during the trunk-hunting operation, have access to a large number of terminals. This trunk-hunting occurs between the transmission of two sets of impulses by the calling subscriber. It has been found in practice that the speed of the switch is sufficient, in a great majority of instances, to permit of the completion of 25 the hunting operation before the second set of impulses is transmitted to operate a succeeding switch. However, should another set of impulses be started before a switch has found an idle trunk, certain of the impulses would be lost, which would result in the establishment of an incorrect connection.

An object of the present invention is to provide novel means for preventing the incorrect setting of switches should a set of impulses be sent to operate a switch before a preceding one has completed its trunk-hunting operation.

In accordance with this object an impulse-storing mechanism is provided at a switch which will be operated to store impulses intended for a succeeding switch if said impulses are transmitted before the first switch has completed its trunk-hunting operation. When an idle trunk is found, the impulse-storing mechanism is released, and impulses are then transmitted therefrom to operate said succeeding switch.

The inventive idea involved is capable of receiving a variety of expressions one of which, for the purpose of illustrating the invention, is shown in the accompanying drawing; but it is to be expressly understood that said drawing is employed merely

for the purpose of facilitating the description of the invention as a whole and not to define the limits thereof, reference being had to the appended claims for this purpose.

In the drawing the figure illustrates diagrammatically a circuit arrangement and mechanism employed in carrying out the invention.

It is believed that the invention will be fully understood from the following detailed description of the operation. When a call is initiated by a subscriber removing the receiver from its switchhook at sub-station 1, a circuit is closed to operate a line or finder switch (not shown) in a manner well known in the art. The operation of such a switch extends the calling line to an idle selector switch, such as shown in the drawing, whereupon a circuit is closed for line relay 2 extending from grounded battery, right winding of said relay, side switch wiper 3 in position 1, apparatus at sub-station 1, side switch wiper 4 in position 1 and left winding of relay 2 to ground. Energization of relay 2 establishes a circuit for slow-to-release relay 5. The selector is now in condition to receive impulses transmitted from the sending device 6 at the calling sub-station to operate the switch in its primary or group selecting movement. The first deenergization of relay 2 in response to the impulses, establishes a circuit for the second slow-to-release relay 7 extending from grounded battery, winding of said relay, front contact and armature of relay 5 and back contact and armature of relay 2 to ground. Relays 5 and 7, being slow-to-release, maintain their armatures attracted during transmission of the impulses.

Energization of relay 7 establishes a circuit for the escape magnet 8 extending from grounded battery, winding of said magnet, side-switch wiper 9 in position 1, front contact and armature of relay 7 to ground. Magnet 8, in energizing at this time, has no effect upon the side-switch mechanism. Each deenergization of relay 2 also closes a circuit for primary stepping magnet 10, traceable from grounded battery, winding of said magnet, side-switch wiper 11 in position 1, front contact and armature of relay 5 and back contact and armature of relay 2 to ground. Magnet 10 moves brushes 12,

13 and 14 of the switch in accordance with the impulses transmitted to step said brushes in a group selecting movement. At the termination of the impulses relay 2 remains energized and thus opens the circuit for relay 7, which, after an interval, releases. The deenergization of relay 7 opens the circuit for magnet 8, which thereupon releases and moves the side-switch wipers 5 into position 2. When side-switch wiper 15 moves into its second position a self-interrupting circuit is established for secondary stepping magnet 16 and the brushes 12, 13 and 14 of the switch are stepped, in a trunk- 10 hunting movement, over the terminals of the selected group until an idle trunk is found, this condition being denoted by ground at test terminal 17. When an idle trunk is reached a circuit is established for 15 escape magnet 8, extending from grounded battery, winding of said magnet, side-switch wipers 9 and 18 in position 2, brush 14 and terminal 17 to ground. Energization of magnet 8 moves the side-switch wipers 20 to position 3.

If, during the trunk-hunting operation, sending device 6 has not been operated to transmit a second set of impulses intended for the next succeeding switch, the impulse 25 storing mechanism, generally indicated by the numeral 19, will remain inactive. Escape magnet 8, upon reaching position 3, will find another energizing circuit for itself extending through the side-switch wiper 9, 30 sliding contact 37, contact 20 of the impulse-storing mechanism, contact spring 21, sliding contact 38 and back contact and armature of relay 7 to ground. Magnet 8 will again energize and move side-switch wipers 35 into position 4 whereupon relays 2 and 5 will release. The calling line is now extended to the next succeeding switch, which may be similar to the switch shown. Impulses now transmitted from the sending 40 device 6 will operate said succeeding switch and the extension of the call may continue through other switches until the called line is reached.

At the termination of a conversation, the 45 replacing of the receiver upon the switch hook at substation 1, will cause a ground to be applied to release conductor 22, in a manner well-known in the art, and thus establish a circuit for release magnet 23. This magnet, in energizing, closes a locking circuit for itself from grounded battery through its winding, armature and front contact and off-normal contact 24, which was closed upon the first step of the switch 50 from its normal position, to ground. Magnet 23 operates to restore brushes 12, 13 and 14 and the side-switch mechanism to normal, whereupon contact 24 is opened and magnet 23 is thus permitted to release.

55 Assuming now that while the side-switch

wipers are in position 2 and the switch is performing its secondary or trunk-hunting operation, the calling subscriber manipulates sending device 6 to transmit a second set of impulses designed to operate a succeeding switch, relay 2 will respond to each interruption in the same manner as before. A circuit will then be established for magnet 25 of the impulse-storing mechanism 19, which circuit is traceable from grounded 70 battery, winding of said magnet, side-switch wiper 11 in position 2, front contact and armature of relay 5 and back contact and armature of relay 2 to ground. If, during the transmission of these impulses, the 75 switch should find an idle trunk and the side-switch wipers move into position 3, magnet 25 would continue to step in response to the impulses over a circuit which now extends through side-switch wiper 11 80 in its third position. In response to each impulse, magnet 25 operates pawl 26 to step ratchet 27 in a counter-clockwise direction. Ratchet 27 is connected to impulse wheel 28 by a spring 28' or other similar device, 85 which will be tensioned as ratchet 27 is rotated so that wheel 28 will also be rotated when the same is released by the holding pawl 29 normally in engagement with a tooth thereof. Upon the first step of ratchet 90 27, contact 20 is disengaged from the spring contact 21 and contacts 30 and 31 are permitted to engage. This is accomplished by normally tensioning springs 21 and 30 by the pressure thereagainst of a pin 30' carried by the impulse wheel 28. Therefore, should the switch find an idle trunk while the second set of impulses are still being transmitted and the side-switch wipers move 95 into position 3, the previously described circuit for escape magnet 8, extending through contacts 20 and 21, will not be closed and the side-switch wipers will thus be prevented from moving into position 4 until off-normal contact 20 is restored. When side-switch wiper 32 moves from position 2 into 100 position 3 at the termination of the trunk-hunting operation, the end of said side-switch wiper trips the holding pawl 29, and disengages said pawl from impulse wheel 105 28. Under the influence of the spring connecting ratchet 27 and wheel 28 and a speed controlling governor 27' of any well-known type, the wheel 28 is then rotated in a counter-clockwise direction and the teeth 110 thereof operate lever 33 to open the contact 34. If at the end of the trunk-hunting operation, and after wheel 28 is released, impulses continue to be transmitted, the ratchet 27 will be stepped in the same manner as 115 before and the storing mechanism will then simultaneously receive and send out the impulses.

120 The spring contacts 30 and 31 being now closed to bridge the telephone line and side- 125 130

switch wiper 35 being in position 3, it will be apparent that each opening of the contact 34 will interrupt the line circuit extending through brushes 12 and 13 to step the next 5 succeeding switch in accordance with the impulses transmitted. As soon as impulse wheel 28 again assumes its normal position with respect to ratchet 27, pin 30' engages contact 30 to disengage it from contact 31 10 and at the same time cause spring 21 to again engage contact 20. The previously described energizing circuit for escape magnet 8, through contacts 20 and 21 is thereby again established and said magnet energizes 15 to move side-switch wipers from position 3 into position 4.

When the side-switch wiper 32 is restored to normal upon the release of the switch, holding pawl 29 is again permitted to engage the impulse wheel 28 and the impulse-storing mechanism will be in position to again be operated.

What is claimed is:

1. In a telephone system, automatic 25 switches having a plurality of movements, means for sending a series of impulses to operate one of said switches in its primary movement, means for operating such switch in its secondary movement for extending a connection to the succeeding switch, means for transmitting a subsequent series of impulses over said connection to operate the succeeding switch, a register device, and means for rendering said 30 subsequent series effective to set the register device when sent before the completion of the secondary movement of the first mentioned switch.

2. In a telephone system, automatic 40 switches having a plurality of movements, means for sending a series of impulses to operate one of said switches in its primary movement, means for operating such switch in its secondary movement for extending a 45 connection to the succeeding switch, means for transmitting a subsequent series of impulses over said connection to operate the succeeding switch, a register device, means for rendering said subsequent series effective 50 to set the register device when sent before the completion of the secondary movement of the first mentioned switch, and means for operating the register device to send a series of impulses to the succeeding switch 55 corresponding to said subsequent series.

3. In a telephone system a line, automatic switches having a plurality of movements, a sender for sending series of impulses over said line to operate one of said 60 switches in its primary movement, means

for operating said switch in its secondary movement for extending a connection to the succeeding switch, means for transmitting a subsequent series of impulses sent over said line to the succeeding switch provided the first mentioned switch has completed its secondary movement prior to the sending of the subsequent series, a register device, means for rendering the subsequent series of impulses effective to set said register device when sent before the completion of the secondary movement of the first mentioned switch, and means for subsequently operating the register device to transmit a series of impulses to the succeeding switch. 65 70 75

4. In a telephone system, automatic switches having a plurality of movements, means for sending a series of impulses to operate one of said switches in its primary movement, means for operating such switch 80 in its secondary movement to extend a connection to the succeeding switch, means for transmitting a subsequent series of impulses over said connection to operate the succeeding switch, a register device, means for rendering said subsequent series of impulses effective to set the register device when sent before the completion of the secondary movement of the first mentioned switch, and a switch auxiliary to said first mentioned 85 90 95 switch operable to start said register device in operation to transmit a series of impulses corresponding to said subsequent series to the succeeding switch.

5. In a telephone system, a train of automatic switches having primary and secondary movements, an impulse sender for setting the first switch in its primary movement, means thereupon automatically operated to give said switch a secondary movement to select an idle trunk, an impulse storing mechanism operatively associated with said sender during such hunting movement and set thereby should said sender be operated before the idle trunk is seized, means 100 operated by the seizure of the idle trunk and restoration of the sender for causing said impulse storing mechanism to operate to set the succeeding switch in its primary movement, and means actuated should the 105 trunk be seized before the sender is operated to disassociate the impulse storing mechanism from the sender and render the latter effective to control the succeeding switch in its primary movement. 110 115

In witness whereof, we hereunto subscribe our names this 17th day of July, A. D. 1919.

HENRY P. CLAUSEN.
CHARLES L. GOODRUM.
